CLOSURE

Joseph E. Valentine, Plainfield, N. J., assignor to
 Oxxyn Sales Company, a corporation of New
 Jersey

Application February 5, 1940, Serial No. 317,416

5 Claims. (Cl. 132—78.5)

This invention relates to closures, and more particularly to decorative closures for such articles as powder puffs and the like, and as such is an improvement upon my prior Patent 5 1,813,518 of July 7, 1931.

The objects of the invention are: to provide an improved closure which will enhance the appearance of the article; to provide an improved closure for a flexible article which has to be turned inside out through an opening before effecting the sealing of the opening by the closure; to provide a closure of the character indicated which will enable contrast of color to be obtained thereby in a powder puff or the like; to minimize the parts necessary; to minimize time, operations and difficulties in the steps of assembly; to obtain an appearance of shirring of the fabric around the closure; to avoid hand stitching of the article or closure in effecting the final seal; to provide a method of manufacture which will increase output and lower costs and yet produce an article of improved character; to employ a part in making the closure which will add to the firmness of the mid-portion of a powder puff or the like for holding purposes; and to secure other advantages and results as may be brought out in the following description.

Referring to the accompanying drawing in which like numerals of reference indicate similar parts throughout the several views:

Figure 1 is a perspective view of a powder puff embodying the present invention;

Figure 2 is a similar perspective view with the powder puff partially assembled;

Figure 3 is a similar perspective view with the puff ready to begin assembly;

Figure 4 is a sectional view on line 4—4 of Figure 2, but with the cap in place ready to be secured;

Figure 5 is a sectional view on line 5—5 of Figure 1;

Figure 6 is a perspective view of the preferred form of ring or collar as it appears after being crimped in place;

Figure 7 is a perspective view of a modified construction of powder puff with a ruff around the closure;

Figure 8 is a perspective view of the several parts, one above the next in order of assembly, 50 which are used in effecting the closure of Figure 7;

Figures 9 and 10 are sections and Figure 11 a plan of three different forms of ring or collar which may be employed in the assembly of the 55 closure.

In the specific embodiment of the invention illustrated in said drawing, the article which is to be sealed by the closure is shown to be a powder puff of the type which provides a front or powder- 60 applying member 15 and a back member 16 of

silk or other suitable fabric or material. The front member is some such material as pile-fabric, lamb-skin or the like. In the manufacture of powder-puffs and the like, it is common practice to place the two members face to face, 5 wrong side out and right side in. Accordingly the pile surface of the front member is first placed toward the ultimate outside surface of the back member and the two members stitched entirely around their juxtaposed peripheries. In order to be enabled to thereafter turn the members right side out, criss-cross slits 17 are cut in the back member at the center thereof, thus establishing a central opening. This opening must be closed in order to provide the powder puff 10 with a finished appearance, and the problem of economically, and at the same time pleasingly, close this opening has not been, up to the present 15 time, satisfactorily solved.

According to the present invention, and dealing initially with the showing thereof exemplified in Figures 1 to 6 inclusive, a ring or collar 18 is provided, which, in its originally manufactured configuration is of right-angle cross-section. That is to say, the ring provides a flat base ring portion 19 from the outer periphery of which is an upstanding wall or cylindrical portion 20. The ring or collar is preferably of a bendable metal, such as thin aluminum or other metal or alloy which can be ultimately crimped without injury to the fabric or other materials used in the powder-puff. The ring is also of slightly greater diameter than the length of either slit 17, and may be inserted into the puff (after the puff is turned right side out) by appropriate distortion of the fabric of the back member during the insertion. The ring is centered with respect to the puff and slits with the upstanding wall 20 of the ring making edge engagement under the inside surface of the back member. Thereafter a flat disc or cap 21 of appropriate size to fit within the upstanding wall 20 but too large to pass through the base portion 19, is pressed into the ring (see Figures 2 and 4) thereby including the portion of the back material contiguous 45 to the slits between the cap and ring. The slits are accordingly hidden by the cap. Thereafter the upstanding wall is crimped inward, thereby gripping the back material and cap and securely holding those parts assembled.

The crimping of the side wall is preferably accomplished by a suitable die, and as the back material overlies the edge of the ring, it is essential to use material for the ring which will respond to the pressure of the die without injury to the fabric. The die may have appropriate shape to apply the desired form of crimping, and according to the present showing the crimping is preferably serrated or wavy, as represented by Figures 1, 5 and 6. By so crimping 55 60

the ring or collar, there is not only less likelihood of damaging the material of the back member, but the said material is given a desirable appearance of stirring toward the center, as shown.

5 The cap 21 may be made of suitable material such as a cardboard base 22 suitably faced, as at 23, with fabric or other facing material and is conducive to contrast in color or other decorative finish to the body portion of the puff. The 10 cap is furthermore a convenient unit which can be readily printed with appropriate lettering, such for instance, as by an initial 24 where the same is desired. The ring and cap when gripped in the finished puff furthermore provide a desirable firmness to the mid-portion of the puff for holding purposes by the user. Very little slow or tedious hand work is required in manufacture, and as the puff is thereby largely a machine-made product, its cost is comparatively low to 15 20 puffs now being marketed.

Referring now to Figures 7 and 8 more particularly, the essential elements above described are present, and like numerals of reference have accordingly been applied. This showing adds a 25 ruff 25. Such ruff is preferably fabricated as a disc or other member of greater size than the cap and of a pliable material, such as a sized or starched fabric, a cellulose material, crepe or other paper, and the like. This member is applied, in manufacture of the puff, over the central portion of the puff back member after the collar has been properly situated in the puff. Then cap 21 is pressed into place, situating the mid portion of the ruff between the cap and collar but with the edges of the ruff projecting. Then the crimping die is applied, for crimping the collar and for also spreading the edge of the ruff outwardly away from the cap. The action 30 35 of the die creases the ruff and in consequence of the creasing and semi-stiffness of the ruff material, it retains the spread and stirred status to which it is pressed. The presence of the material of the ruff between the backing material of the puff and the die lessens the possible injurious effect of the die on the more delicate backing material. The ruff also presents additional possibilities of color combinations and will offer more aesthetic appeal to some purchasers than the plainer finish of puff not having the ruff.

40 50 While, in the foregoing description, use of metal for the ring, and use of fabric and other materials, have been specifically mentioned for various parts recited, it is to be understood mentioning of particular materials is only for purposes of illustration and are not used as restrictive terms. Furthermore, while a circular puff and circular rings or collars have been shown, other shapes of those and other parts may be employed as found desirable.

55 60 In Figures 9, 10 and 11 are illustrated modified structures of ring, and any or all of the rings may be of soft rubber. In these figures, the upper portion of the ring is preferably given a normal inward slope to overlie the under or base portion of the ring. In Figure 9, the upper portion 26 of the ring is of approximately the same width as the lower portion 27 and is shown smooth both at its inner periphery and on its upper face. In use of this modified form, the back facing material of the puff will receive no stirring effect from the ring.

65 70 In Figure 10 the upper portion 28 of the ring also projects inwardly over the base portion 29

as in the preceding modification. However, in this showing the upper face of the upper portion 28 is serrated, as at 30, so that in the assembled puff the backing material will present a stirred effect.

5 10 15 In Figure 11, the upper portion 31 of the ring projects over the base portion 32 similar to descriptions above given, but in this instance the inwardly directed periphery of the upper portion is serrated, as at 33. This construction will also give the desired stirred effect to the back material of the puff.

Inasmuch as these rings of Figures 9, 10 and 11 are of pliable rubber, the upper portions 26, 28 and 31 respectively may be sprung outward 15 to admit the cap, and will, by their resiliency return to normal position for retaining the assembled puff in its assembled condition. However, if found desirable, an adhesive may be applied to the inside surfaces of the rubber rings 20 and/or to the under peripheral margin of the cap or elsewhere for assuring unseparability of parts.

I claim:

1. A closure for an opening in material of 25 which a part of the material projects into the opening, a ring under the material around the opening, and a cap over the material and within the ring, said ring gripping the material above and below the cap at the peripheral margin 30 thereof.

2. A closure for an opening in material of 35 which a part of the material projects into the opening, a ring under the material around the opening, and a cap over the material and within the ring, said ring being pinched inwardly over the cap and thereby gripping the material above and below the cap at the peripheral margin of the cap.

3. A closure for an opening in material of 40 which a part of the material projects into the opening, a ring under the material around the opening, and a cap over the material and within the ring, said ring being of metal and pinched at intervals therearound inwardly over the cap 45 thereby obtaining a serrated surface on the ring and in the same material, the pinched portions of the ring gripping the material above and below the cap at the peripheral margin of the caps.

4. A closure for an opening in material of 50 which a part of the material projects into the opening, a ring under the material around the opening, and a cap over the material and within the ring, said ring being of rubber and providing portions which are inherently resiliently 55 pressed toward each other for gripping the material above and below the cap at the peripheral margin thereof.

5. A closure for an opening in material of 60 which a part of the material projects into the opening, a ring under the material around the opening, a second piece of material larger than the ring and situated over the opening, and a cap over the mid-portion of the second piece of material and the opening, said cap being pressed 65 into the ring, and said ring gripping the material having the opening as well as the second piece of material and cap, and the rim of the second piece of material extending outwardly away from the cap and forming a protection adjacent the 70 ring for the material having the opening and also forming a ruff around the cap.

JOSEPH E. VALENTINE.
